UNITED STATES PATENT OFFICE.

ALFRED R. McCANN, OF HAMILTON, OHIO.

CLAMPING DEVICE FOR OPEN-SIDE PLANERS.

Application filed June 3, 1927. Serial No. 196,278.

My invention relates more particularly to knee clamping devices for open side planers. The objects of my invention are to facilitate the clamping of the knee, carrying the rail, to the housing and thereby insuring greater rigidity of the locked knee upon the housing; to enable the operator to stay in his regular place of operation while clamping or unclamping the knee; to make it unnecessary 10 to use a wrench for loosening certain bolts and nuts used in previous clamping devices, thereby effecting a great saving of time in making the adjustment; to provide a greater surface bearing of the knee on the housing, 15 thereby making it more durable and longer lived and to compensate for the wear of parts by the novel means for making the necessary adjustments.

My invention consists in providing the 20 face of the housing with deep wide dovetailed slots, one of which receives a stationary tapered gib which is provided for the purpose of taking up wear between the knee and the housing, and the other of which slots is provided with a movable tapering gib whereby on moving said gib longitudinally, the knee is readily and securely clamped to the housing or unclamped therefrom, as desired.

30 My invention also consists in the construction, combination, location and arrangement of parts, as herein set forth and claimed.

In the drawings:

Fig. 1 is a plan view of a metal planing machine having my invention embodied therein;

Fig. 2 is a vertical section on the line 2—2 of Fig. 1;

Fig. 3 is an enlarged detail front elevation of the gib and mechanism used in raising 40 and lowering said gib;

Fig. 4 is a front elevation, on an enlarged scale, showing the worm, worm-wheel and crank suitably mounted within its casing, the cover of which is removed, the crank being 45 shown in dotted lines; and

Fig. 5 is a view partly in section and partly in elevation the section being on the line 5—5 of Fig. 1.

In the embodiment of my invention as illustrated and which shows a preferred construction, 1 represents the housing of an open side planer, the face of which is provided with dove-tailed slots 2 and 3, respectively. Knee 4 of the planer is provided with dove-

tailed tongues 5 and 6, respectively, which 55 are adapted to slidably fit within said slots 2 and 3, respectively. Edges 7 and 8 of tongues 5 and 6, respectively, are tapered towards the bottom of said knee 4, as clearly shown in Fig. 5.

Locking gib 9, located between knee 4 and housing 1 is adapted to have a wedging action between edge 7 of knee 4 and edge 10 of housing 1, thereby securely holding or locking said knee against vertical movement on 60 housing 1, as hereinafter more fully described. The upper end of locking gib 9 terminates in laterally extending ear 11, which is provided with hole 12 for the purpose of receiving the lower end 13 of screw 14. The 70 lower end 13 of said screw 14 is fixed within hole 12 of ear 11 by pin 15, as shown in Fig. 2.

The bevel gear bracket 16, clearly illustrated in Figs. 2 and 3, respectively, is mounted upon the top 17 of knee 4 and receives 75 bevel gear 18 and shaft 19 which are rotatably mounted therein. Said bevel gear 18 is rotatably held within bracket 16 by collar 20 and screw 21. Pinion 22 is fixed upon one end of shaft 19 and is in meshing engagement 80 at all times with bevel gear 18. Fixed to the other end of said shaft 19 is worm wheel 23 suitably mounted within casing 24, as shown in Fig. 4. One end of shaft 25 is rotatably mounted within bearing 26 in casing 24 and 85 worm 27 is secured thereto and is in meshing engagement with worm wheel 23. The other end of said shaft 25 terminates in squared end 28 for the purpose of receiving hand crank 29.

One end of shaft 25 is rotatably supported by shaft bearing 30, the latter being rigidly attached to end 31 of cross rail 32, by bolts 33, as shown in Fig. 1. Adjustable gib 34 is tapered similar to locking gib 9 and fits between edge 8 of knee 4 and edge 35 of housing 1, as clearly shown in Fig. 5. The upper end of said gib 34 is provided with laterally extended ear 36 having hole 37 therein which receives threaded stud 38.

To take up any wear between knee 4 and 100 housing 1, simply loosen nut 39 and tighten nut 40, thereby forcing said gib 34 downwardly. When the locking gib 9 is drawn upwardly, thereby releasing knee 4 upon housing 1, retaining member 41, fixed to said knee 4 by bolts 42, assists in supporting the 105 weight of said knee 4 and cross rail 32, thereby allowing said knee and rail to be freely

raised or lowered upon said housing 1, as desired.

The operation of my invention is as follows:

- 5 Assume that knee 4 has been adjusted vertically upon housing 1 to the desired working position and that it is desired to lock said knee and cross rail upon said housing in said adjusted position, all that is necessary, upon 10 the operator's part, is to turn crank 29 in a clockwise direction, thereby turning shaft 25 and worm 27 in a similar direction. Said worm being in meshing engagement with worm wheel 23, causes said worm wheel to be 15 rotated, which, in turn, rotates shaft 19 and pinion 22. Said pinion 22 being in meshing engagement with beveled gear 18 causes said gear to be rotated within bevel gear bracket 16, and thus causes screw 14 to move downwardly, which, in turn, imparts downward movement to locking gib 9, thereby wedging 20 said gib between edge 7, of knee 4, and edge 10, of housing 1.

To unlock the knee relative to the housing, 25 simply reverse the operation just described, or, in other words, turn crank 29 in an anti-clockwise direction, which, in turn, raises locking gib 9, or withdraws it from wedging engagement between edge 7, of knee 4, and 30 edge 10, of housing 1, as previously described.

It will be understood, of course, that the usual means such as screw 43 and other connecting parts not shown for raising and low-

ering the knee, will be used but form no part 35 of this invention.

Certain changes and modifications of my invention can be made without departing from the scope or spirit thereof as defined in the claim, as for instance, worm 27 and 40 worm-wheel 23 may be replaced by an ordinary set of bevel-gears.

What I claim as new and desire to secure by Letters Patent is:

In a clamping device for an open-side 45 planer having a housing with spaced apart dovetailed vertical slots on its face, a knee having dovetailed tongues adapted to enter and engage the dovetails of said slots, respectively, in combination with a movable gib 50 interposed in one of said slots between said knee and housing, a screw fixed to said gib, a bevel gear threaded to said screw and rotatably mounted upon said knee, a second bevel gear rotatably mounted upon said knee 55 and in permanent meshing engagement with said first-mentioned gear, a shaft, one end of which is fixed to said second bevel gear, a worm wheel fixed to the other end of said shaft, a worm meshing with said worm wheel, and manually operative means for turning 60 said worm whereby said gib is adapted to be moved into wedging engagement between said knee and housing, or withdrawn from wedging action between said knee and housing 65 at will.

ALFRED R. McCANN.
